UNITED STATES PATENT OFFICE.

LOUIS WOJIDKOW, OF BROOKLYN, NEW YORK.

DESIGN FOR A KETTLE.

SPECIFICATION forming part of Design No. 25,479, dated May 12, 1896.

Application filed April 11, 1896. Serial No. 587,224. Term of patent 3½ years.

To all whom it may concern:

Be it known that I, LOUIS WOJIDKOW, a citizen of the United States, residing at Brooklyn, in the county of Kings and State of New York, 5 have invented and produced a new and original Design for Kettles, of which the following is a specification, reference being had to the accompanying drawing, which shows a perspective view of the same.

10 The leading feature of my design consists of a kettle-body having the outline as shown—that is, with curved sides bulging outwardly until within a short distance of its lower side, where they suddenly curve inwardly to meet

15 a shallow and contracted base, said body having a spout extending therefrom and two curved arms joined by a curved handle.

A represents the body of the kettle, having the outline as shown, the sides of which bulge outwardly and its lower end contracted into 20 a shallow base B.

C is the spout, and D D represent two curved arms, ornamented, as shown, and joined by means of the curved handle E.

What I claim is—

25 The design for a kettle substantially as herein shown and described.

LOUIS WOJIDKOW.
